UNITED STATES PATENT OFFICE.

CHARLES MUNTER, OF NEW YORK, N. Y.

HOOK OR STUD.

1,345,621.

Specification of Letters Patent.

Patented July 6, 1920.

Application filed December 5, 1917. Serial No. 205,628.

To all whom it may concern:

Be it known that I, CHARLES MUNTER, a citizen of the United States, residing in the city of New York, borough of Manhattan, county and State of New York, have invented a certain new and useful Hook or Stud, of which the following is a specification.

This invention is a hook or stud for lacing, and, while the same may be employed with shoes, leggings, or any other article of wearing apparel, it is particularly adapted for use with corsets, brassières, etc.

The object of the invention is to provide a hook or stud which may be easily and economically manufactured, may be readily applied to a garment, and one which will not be open to the objection, which is almost universal among studs, that it will catch the goods, the structure of this invention being so constituted that the goods cannot possibly catch over the hook and become torn, as has heretofore generally been the case. A further object of the invention is to provide a hook or stud which will coöperate with the lacing in such manner as to lock the lacing against inadvertent disengagement therefrom.

The invention further consists in an improved manner of forming the hook or stud through the swaging and subsequent bending of a blank in a manner hereinafter more fully explained.

Features of the invention, other than those specified, as well as the advantages thereof, will be apparent from the herein-after detailed description taken in conjunction with the accompanying drawings.

In the accompanying drawings I have illustrated one practical embodiment of the invention, but the construction therein shown is to be understood as illustrative, only, and not as defining the limits of the invention.

Figure 1 is an elevation of the blank from which the stud is formed.

Figs. 2, 3 and 4 are sections on the lines 2—2, 3—3, and 4—4, respectively, of Fig. 1.

Fig. 5 is a view corresponding to Fig. 1, but showing the blank as swaged into the desired shape.

Figs. 6, 7 and 8 are cross-sections on the lines 6—6, 7—7, and 8—8, respectively, of Fig. 5.

Fig. 9 is a side elevation of the construction of Fig. 5. 55

Fig. 10 is a view of the construction shown in Fig. 9 after the blank has been bent into final shape.

Fig. 11 shows the construction of Fig. 10 60 partly in central section, and

Fig. 12 shows the stud in place upon the material with which it is adapted to be associated.

In forming the stud of this invention, a 65 blank A is first provided of the general shape shown in Fig. 1, the configuration thereof simulating that of a dumb-bell. The blank embodies two globular sections A and B, united by a shank D, circular in cross- 70 section. Section B constitutes the head of the stud, section D the shank thereof, and section A that portion thereof which is adapted to be manipulated to form the base and attaching portion. 75

A blank of the character shown in Fig. 1 having been provided, section A is swaged into the shape shown best in Figs. 5 and 7, during which operation section A is flattened out into a circular plate E, while the 80 center thereof is stamped out and wiped downwardly into the form of a tubular sleeve F, the lower end of which is preferably serrated, to form tapering tongues or points G, during the stamping and forming 85 operations.

The interior of sleeve F forms a socket H into which head B is caused to protrude by the next operation, which consists in bending shank D upon itself after the manner shown in Figs. 10, 11 and 12. In the preferred construction, shank D is bent, as at d, to such extent that head B extends well into socket H, preferably for substantially one-half the diameter of the head. 95

A stud constructed and formed as described may be readily secured to any material I by simply providing an aperture i through which the sleeve portion F of the stud may be passed, whereupon the points 100 G are bent outwardly to grip the material I between the plate E and said points, as clearly shown in Fig. 12.

The advantages of the stud are numerous. In the first place, it will be apparent that, 105 since head B projects to an appreciable extent down into socket H, it is absolutely impossible, when the stud is secured to a gar-

ment for other portions of the garment to get caught over the head and become torn, as is generally the case in prior devices. In the second place, shank D is circular in cross-section, so that there will be no tendency whatsoever to cut the lace associated with the hook, and said lace will slip more readily through the hook, in tightening the lace, after the same has been brought into 10 coöperative relation therewith. Thirdly, head B projects well into socket H, which leaves but slight clearance between the head and the socket walls. In applying a lace to the stud, the lace is simply slipped beneath the head B, slightly more than half of which head projects above plate E, which construction, coupled with the resiliency of bent portion d of shank D, permits of the lace being readily slipped under the head 15 20 25 30 35 40

into the loop of the stud. When the lace is pulled tight, it may be sprung over the head, due to the resiliency at the bend d of the shank. It, of course, requires the same tension to release the lace from the hook, and, accordingly, the lace cannot become inadvertently disengaged from said hook. Even though it become untied, it will remain in coöperative relation to the hook. Fourthly, as head B extends well into socket H, the structure of the stud is made very compact and the stud does not extend to an objectionable distance away from the garment, as is frequently the case in prior devices. Other advantages, such as the ease of securing the stud to a garment, the ease and economy of manufacture, and the strength due to the integral construction, will be apparent to those skilled in the art, as will be other advantages inherent in the stud.

The stud may be made in different sizes, in accordance with the environment in which it is to be used, and may be slightly differed in shape or configuration, without departing from the spirit of the invention, which is to be understood to be as broadly novel as is commensurate with the appended claims.

Having thus fully described the invention, what I claim as new, and desire to secure by 50 Letters Patent, is:

1. A stud or hook embodying an attaching portion provided with a socket, a resilient hook shaped portion integral with the attaching portion and provided with a ball shaped end extending an appreciable distance into the socket, said ball shaped end being of substantially the same diameter as the diameter of the socket, whereby a constricted annular space is left between the 60 ball shaped end and the wall of the socket, through which space a lace is adapted to be passed into engagement with the hook shaped portion, said hook shaped portion yielding slightly to allow of the passage of 65 the lace between the ball shaped end and the wall of the socket.

2. A hook or stud embodying an attaching portion provided with a socket, a hook shaped portion integral with the attaching portion and provided at its end with a spherical knob extending into the socket and the attaching portion to such extent that it is necessary to spring the hook shaped portion in order to draw the lace thereover and 70 between its spherical end and the walls of the socket, said hook shaped portion being curvilinear in cross section throughout 75 whereby the cutting of the lace is obviated.

3. A stud or hook embodying an attaching portion provided with a socket, a resilient hook shaped portion integral with the socket and formed at its free end to project an appreciable distance into said socket and occupy the major portion of the mouth 80 thereof whereby, when a lace is drawn over the hook shaped portion the hook is sprung to allow of the passage of the lace between the free end of the hook shaped portion and the wall of the socket, the lace being thereafter resiliently locked in place against inadvertent disengagement from the stud.

In testimony whereof I have signed my name to this specification.

CHARLES MUNTER.
